G. Franklin Mayes

ATTORNEY

UNITED STATES PATENT OFFICE.

CHARLES T. DAVIS, OF BEACON, NEW YORK, ASSIGNOR TO DAVIS & GECK, INC., OF BROOKLYN, NEW YORK, A CORPORATION OF NEW YORK.

NEEDLE.

Application filed September 27, 1924. Serial No. 740,253.

This invention is an improvement in needles, and with respect to its more specific features, in needles designed for surgeon's use.

- 5 With surgical needles, it is desirable that there be a substantially smooth surface from the point of the needle to the remote end of the suture, and a substantially uniform taper from the point to the suture, in order 60
10 that the suture may pass easily through the perforation made by the needle with a minimum of injury to the tissues and of pain to the patient.

With the usual construction of eyeletted 15 needle, when it is threaded, two thicknesses of thread are added to the diameter of the needle at the eye. The opening made by the needle must be materially enlarged to permit the passage of this bulk, which more- 20 over, has its large end toward the opening, presenting thus a large, blunt obstruction to the further passage of the needle.

The advantages in smooth and easy passage with gradual dilation of the needle 25 opening and consequent slight bruising and crushing of the tissues, accruing from the smooth surface and uniform taper of the needle, are nullified by the abrupt increase in diameter due to this bulk. Such constructions are also objectionable in that the 30 loose end of the suture is liable to slip through the eye, necessitating a halt in proceedings for rethreading.

With the object of eliminating this ob- 35 jectionable enlargement, needles have been made with axial sockets for receiving the suture, and in which the suture is held end to end, and in axial alinement with the needle.

40 The formation of the socket is an operation of some delicacy, and to facilitate such operation, as well as to provide a convenient means to secure the suture in the socket, the socket end of the needle is untempered, 45 which necessitates that the ends of the needle receive different treatment.

One of the objects of the present invention is to provide a needle especially de- 50 signed for surgeons' use, but suitable for other purposes, wherein a socket is pro- vided without necessitating boring of the needle, and without requiring different treatment for the needle ends.

With these and other objects in view, the 55 invention consists in the construction and

novel combination of parts fully described hereinafter, illustrated in the accompanying drawings, and pointed out in the claims appended hereto, it being understood that various changes in the form, proportion, size 60 and minor details of construction, within the scope of the claims, may be resorted to without departing from the spirit of the invention.

In the drawings:

Fig. 1 is a longitudinal section of one of the elements of the improved needle.

Fig. 2 is a plan view of the other ele- 65

ment.

Fig. 3 is a longitudinal section of the 70

parts or elements assembled.

Fig. 4 is a similar view of an alternate

arrangement.

Fig. 5 is a similar section after the point- 75

ing of the needle.

Fig. 6 is a plan view with parts broken

away, showing the needle assembled with

the suture.

Fig. 7 is a plan view of the finished

needle.

In the present embodiment of the invention the improved needle is composed of two parts or elements, namely, the shell or outer part 1, and a center or inner part 2. The latter part is a cylindrical body, of tem- 85
90
95

pered material, as for instance, a piece of high carbon steel wire, highly tempered,

while the shell is of softer material, as for

instance steel tubing, annealed and of a

size and bored to snugly fit the suture. (Fig. 3).

The shell 1 is of greater length than the center, so that when the parts are assembled,

the shell will extend beyond one end of the

center to form a socket for receiving the 95

suture.

The parts may be assembled as shown in

Fig. 3, with the ends of the parts remote

from the socket flush or they may be as-

sembled as shown in Fig. 4, with the ele- 100

ment 2 extended beyond the element 1, at

the end remote from the socket.

The parts are assembled, either in the

manner shown in Fig. 3, or that shown in

Fig. 4, and the shell is secured to the center, 105

by shrinking, sweating, or in any other

suitable manner, after which the point 5 is

formed on the needle.

It will be understood that the point 5 may

be of any desired cross section, circular, or 110

polygonal, and it is formed in any suitable manner as for instance, by grinding. When the parts are assembled as shown in Fig. 3, a considerable portion of the shell must be ground away, while in the Fig. 4 assemblage a much less quantity must be ground, but the final product is the same.

After the grinding of the point, the needle presents at one end a point and at 10 the other a socket of a size suitable to receive the end of the suture, and the needle is connected to the suture by placing the end of the suture in the socket. In order to hold the parts together, the free end of 15 the socket is swaged upon the suture, as shown at 8 in Fig. 7. A construction is thus provided, wherein the needle tapers smoothly and uniformly from the point to the suture, and wherein the largest diameter 20 of the needle is larger than the largest diameter of the suture so that there will be no stretching of the needle opening by the suture.

It will be evident from the description, 25 that the completed needle will have a point of the hardest steel, a shank of smooth but softer metal, but with a socket in place of the usual eye. In practice, when the parts

are arranged as shown in Fig. 3, the center 2 will be about $\frac{5}{8}$ of an inch shorter than 30 the needle, so that the socket will measure $\frac{5}{8}$ of an inch in depth. The depth of the socket is the same in the Fig. 4 arrangement.

While the improved needle will usually be composed of a tempered center and a 35 softer shell, it will be obvious that both center and shell might be of the same material, similarly tempered.

I claim:

1. The method of making needles, which 40 consists in securing on a tempered shank, a closely fitting seamless shell of softer material, with one end of the shell extending beyond the shank to form a seamless socket, and tapering the other end of the shell and 45 shank to a point.

2. As an article of manufacture, a needle composed of a tempered shank and a closely fitting seamless shell of softer material extending beyond the center at one end to 50 form a socket, the other end of the shank and shell tapered to a point.

Signed at Brooklyn in the county of Kings and State of New York, this 12th day of Sept., A. D. 1924.

CHARLES T. DAVIS.
